SIGNATURE GATHERING MACHINE

Raymond E. Ackley, Evanston, Ill., assignor to
 W. F. Hall Printing Company, Chicago, Ill., a
 corporation of Illinois

Application August 1, 1950, Serial No. 177,072

10 Claims. (Cl. 270—54)

1

This invention relates to gathering machines of the type commonly employed in the printing and binding industry to gather signatures to form books, magazines, etc.

The present invention is particularly concerned with signature gathering machines of the type embodying a plurality of signature hoppers disposed at spaced intervals along an endless conveyor, and a plurality of swinging arms keyed on a shaft for common pivotal movement between their respective hoppers and the conveyor, each swinging arm being provided at its free end with a set of gripping jaws which act to engage and withdraw the bottom signature from its respective pile of signatures and to deliver same onto the conveyor. As the conveyor moves past the several hoppers, a signature is successively withdrawn and delivered from each hopper and onto the conveyor to form a complete set of signatures for delivery to a binding apparatus.

As gathering machines employed to gather signatures for books and magazines are often quite extensive in length and provided with a relatively large number of swinging arms moving in unison toward and away from their respective hoppers, the arm actuating mechanism is thus subjected to severe wear and strain during each reversal of movement of the swinging arms. The present invention contemplates the provision of a gathering machine embodying a plurality of similar sections secured together in end-to-end relation with each section having, for example, a set of 12 swinging arms and individual arm actuating mechanisms to swing its respective set of arms in unison. To reduce wear and strain of the arm actuating mechanism and to provide a more balanced condition of the arms throughout the length of a gathering machine, each set of arms is disposed at a different point in the swing cycle. For example, in a gathering machine embodying four sections, two sets of arms would be disposed at opposite ends of the swing cycle while the other two sets of arms would be disposed at a medial point in the swing cycle for movement in opposite directions. The four sets of arms are equidistantly positioned at different points throughout the swing cycle by providing each set of arms with an individual crank rotatable through an arc of 360°, the four cranks being radially spaced 90° apart about the axis of the crankshaft. In the assembly of gathering machines embodying several sections, the cranks of the several sections are equidistantly spaced about the axis of the crankshaft to thus provide

2

a more balanced condition of the swinging arms and the arm actuating mechanism.

This invention embodies other novel features, details of construction and arrangement of parts which are hereinafter set forth in the specification and claims, and illustrated in the accompanying drawings, wherein:

Fig. 1 is a fragmentary front elevational view of a signature gathering machine embodying features of the present invention.

Fig. 2 is a transverse sectional view taken along the line 2—2 of Fig. 1.

Fig. 3 is a schematic front elevational view illustrating the relative position of the cranks and swinging arms of a four section gathering machine.

Figs. 4, 5, 6 and 7 are schematic transverse sectional views taken along the lines 4—4, 5—5, 6—6 and 1—7, respectively, of Fig. 3.

Referring now to the drawings for a better understanding of the present invention, the gathering machine is shown as comprising four similar sections A, B, C and D, indicated schematically in Figs. 3 to 7, joined together to gather signatures in succession and in proper order to form books. As heretofore pointed out, any number of sections may be joined together, depending upon the number of signatures to be gathered to form a book, and the following description of one section applies to the other sections.

The gathering machine comprises generally a drive shaft 9 journaled at spaced intervals along a frame 10 and adapted to drive an endless conveyor 11 by any suitable power transmission means (not shown). The endless conveyor extends along the front of the machine and is provided at equally spaced intervals with push pins 12 to engage and advance the signatures along the front of the machine to a binding mechanism (not shown). The inner flight of the conveyor travels along a trough 13 provided with a front wall 14 which serves as a stop to engage signatures being delivered to the trough.

Piles of signatures 17 are arranged at spaced intervals along the back of the machine to be gathered successively to form books, each pile being disposed in a hopper 18 embodying a bottom plate 19 and a front plate 21 having their adjacent edges disposed in spaced relation to form an outlet for the withdrawal of the bottom signature in the pile.

Each signature is withdrawn from its respective pile in timed relation with the conveyor 11 by means of a suction mechanism which engages the lower face of a signature and draws its for-

ward edge downwardly through the outlet of its hopper and into position to be engaged by a gripper mechanism. The suction mechanism comprises suction cups 22 communicating with a pipe 23 which, in practice, would be connected with an air suction mechanism (not shown), the pipe being connected by a bracket 24 to a shaft 25. The shaft 25, one of which is provided for each set of suction cups, is connected at its ends with members 26 hingedly connected at 27-27 with a stationary part of the machine. The suction cups are so disposed that when the structure just described is rocked on the hinges 27-27 in a counterclockwise direction, in Fig. 2, the cups pass upwardly through the aperture 20 in the plate 19 and engage for forward edge portion of the bottom signature, and when rocked in the opposite direction will draw this forward edge portion of the signature down through the outlet of the hopper.

The means shown for actuating the suction feed mechanism comprises a link 28 pivotally connected at one end, at 29, with the members 26-26 and at its opposite end with the upper end of an arm 30 rigidly secured to a rock shaft 31 journaled in the frame of the machine and having an arm 32 rigid therewith. A roller 33 is journaled on the arm 32 for engagement with a cam 34 keyed to the drive shaft 9.

The gripper feed mechanisms referred to, one of which is provided for feeding the signatures from each of the piles to position them against the stop wall 14, each comprises a gripper arm 35 keyed on a rock shaft 36 journaled in the frame of the machine, the rock shaft being shown as formed of two longitudinally aligned sections spaced apart (see Fig. 1). The gripper arm 35 is provided at its lower end with a rigid gripper jaw 37 and a movable gripper jaw 38 journaled on a pin 40.

Each of the several sections A, B, C and D of the gathering machine is provided with a rocker mechanism for swinging the several gripper arms 35 embodied in the section. The rocker mechanism is shown as comprising a pair of arms 41 and 42 keyed to adjacent ends of the shaft sections 36 and connected together at their outer ends by a shaft 43. A pitman 44 is pivotally connected at its upper end to the shaft 43 and is journaled at its lower end on a crank 45 formed on the drive shaft 9.

The mechanism for actuating the movable jaw 38 comprises a connecting link 46 pivotally connected at its lower end to said jaw and at its upper end to one end of a rocker arm 48 pivotally mounted at 49 on a bracket 50 carried by the gripper arm 35. A connecting link 52 is pivotally connected at 51 to the rocker arm 48 and has its upper end pivoted at 53 on an arm 54 keyed to a shaft 55 which, in turn, is journaled in a pair of stationary bracket arms 56-56. A sleeve 57 is secured to the shaft 55 and provided with an arm 58 which is pivotally connected at 59 to the upper end of a link 60. The lower end of the link 60 is pivotally connected at 61 to the upper end of a link 62 and also to an arm 63 keyed to a shaft 65 which is journaled in brackets 66-66.

The lower end of the link 62 is pivotally connected at 67 to an arm 68 rigid with a sleeve 69 journaled on the shaft 31. An arm 70 is also formed on the sleeve 69 and provided with a roller 71 for engagement against a cam 72 keyed to the shaft 9. The cams 34 and 72 are so shaped and angularly positioned about the shaft 9 that

as the arm 35 swings to its inner position adjacent the hopper 18 the movable jaw 38 is pivoted upwardly to clamp the forward edge portion of a signature against the fixed jaw 37. As the arm 35 swings toward its outer position, as shown in Fig. 2, the movable jaw 38 is pivoted away from the jaw 37 to discharge the signature onto the conveyor 11.

As heretofore pointed out, Figs. 1 and 2 in the drawings illustrate a single section of a conventional gathering machine embodying, for example 8, 10, 12 or more gripper arms 35 pivotally movable in unison between the hoppers 18 and the conveyor 11 responsive to rotational movement of the crank 45. In the construction of gathering machines embodying, for example, 60 or more gripper arms, it has heretofore been the practice to place several individual sections in end-to-end relation along a conveyor and to pivot the gripper arms of the several sections in unison between the hoppers 18 and conveyor 11. It will thus be appreciated that the simultaneous reversal of pivotal movement of 50 or more gripper arms produces an unbalanced condition and excessive strain and wear throughout the machine.

In order to balance the several sections embodied in relatively long gathering machines, the present invention contemplates having the gripping arms of the several sections disposed in different positions in the swing cycle. For example, as illustrated schematically in Figs. 3 to 7 in the drawings, a gathering machine is shown as comprising four individual sections A, B, C and D disposed in end-to-end relation and having a common crank shaft 9 provided with four cranks 45, 45a, 45b and 45c radially spaced 90° apart about the axis of the crank shaft.

As illustrated in Fig. 4, the first section A of the gathering machine embodies a plurality of gripper arms 35 keyed to shafts 36 and pivoted back and forth responsive to rotational movement of the crank 45, the arms being disposed at the inner end of their swing cycle adjacent their hoppers 18. Fig. 5 illustrates the second section B of the machine in which the gripper arms 35a are keyed to shafts 36a and pivoted responsive to rotational movement of the crank 45a, the arms being disposed at a medial position in their swing cycle and moving toward their respective hoppers 18a. Fig. 6 illustrates the third section of the gathering machine in which the gripper arms 35b are keyed to shafts 36b and actuated responsive to rotational movement of the crank 45b, the arms being disposed at the far end of their swing cycle from their hoppers 18b. Fig. 7 illustrates the fourth section of the gathering machine in which gripper arms 35c are keyed to shafts 36c and swing back and forth responsive to rotational movement of the crank 45c, the arms being disposed at a medial position in their swing cycle and moving away from their respective hoppers 18c.

It will thus be noted that the four sets of gripper arms 35, 35a, 35b and 35c are equidistantly spaced throughout the swing cycle and act to counterbalance each other to reduce vibration, strain and wear. In the construction of gathering machines embodying more or less than four individual sections, a crank is provided for each section and the several cranks are equally spaced about the axis of their common crank shaft to space the several sets of gripper arms at equal distances from each other throughout the swing cycle.

The gripper arms of large conventional gathering machines are equally spaced from each other throughout the length of the machine in order to deliver each signature in proper position upon the conveyor 11. In the present invention the spacing between adjacent sets of gripping arms must be increased or decreased due to the fact that each set of arms is disposed in a different position in the swing cycle. For example, in a gathering machine embodying four sections A, B, C and D, the gripping arms of section A precede the gripping arms of section B one-fourth of a swing cycle. Therefore, the spacing between the last arm of section A and the first arm of section B will be equal to the normal spacing of the arms less one-fourth the distance the conveyor 11 moves during each swing cycle.

It is essential to the operation of a gathering machine of the type described, that the timing of the gripper arm swing have such a relation to the timing of the conveyor chain that the signature carried by the gripper arm be delivered to the conveyor between the carrier pins mounted thereon. This relationship can be brought about in two distinct ways:

1. The timing of the swing of the grippers can be adjusted until the desired relationship exists between gripper arm swing and carrier pin travel.

2. With any timing of the swing of the gripper arm, the desired relationship can be obtained by a proper positioning of the arm or group of arms along the conveyor chain. All possible relationships between the timing of the conveyor carrier pins and the timing of the gripper arms can be exhausted by shifting a section or group of arms through a distance along the conveyor equal to the carrier pin spacing, which corresponds to one cycle of the machine, since the pins move through a distance equal to their spacing during one revolution of the machine. The carrier pin spacing is also the spacing of the signature containers or boxes, and of the gripper arms which remove signatures from these boxes; but although it has hitherto been the custom to make the distance between the arms of successive groups also equal to the carrier pin spacing, I have found that this is unnecessary. After any desired setting of the gripper arm swing has been selected for any section or group of arms, this section can be caused to deliver its signatures between the carrier pins by suitably positioning the section along the conveyor chain. When this has been done, the distance between the last gripper arm of one section and the first arm of the adjacent following section may be equal to (as is now the practice), less than, or greater than the distance between gripper arms within the section, according to the selection which has been made for the timing of the gripper arm swing of the respective sections. That is, the swing of the arm can be adjusted to suit the position of the arm with respect to the carrier pins, or the position of the arm can be adjusted to suit the swing. Either procedure brings about the same result.

It will be noted that with the revolution of the shaft 9 being counterclockwise as indicated by arrows in Figs. 4-7 inclusive (in which the positions of the various sections of arms are shown as of the same instant), gripper arm 35 of group A has reached its maximum forward position, at which time the signature carried by the arm has been positioned between a pair of pins 12 on the conveyor 11. At this same instant, the arm 35a of group B is one-fourth of a cycle behind arm 35 of group A in its movement. Thus by the

time that arm 35a has reached the position corresponding to that shown for arm 35 of group A, the conveyor chain will have advanced one-fourth of the distance between carrier pins, at which time the gripper arm must be in the proper position to release its signature between the pins. In order to insure this, the distance between the last arm of group A and the first arm of group B must be made one-fourth less than the carrier pin spacing (which is also the spacing of the arms within each section).

If the direction of the arrows in Figs. 4-7 were reversed, so that shaft 9 would rotate clockwise, Fig. 5 would then represent the case where arm 35a has completed its outward movement, deposited its signature between the carrier pins, and advanced one-fourth cycle in its return trip to pick up another signature. From this it is evident that in order to deliver a signature between carrier pins, the swing of the arm must have been in proper relation to the travel of the carrier pins one-fourth cycle earlier. To secure this condition, the distance between the last arm of group A and the first arm of group B would have to be one-fourth greater than the spacing of the arms within the sections.

The above also applies to the relations between group B and group C, and also between group C and group D.

Similar arrangements can be worked out for a different number of sections than four. All possible arrangements can be covered, however, by the condition that a group of arms, whatever the timing of their swing may be, can always be caused to deliver their signatures between the carrier pins on the conveyor chain by suitably choosing the position of the group with respect to the conveyor.

Since the purpose in view is to distribute the operating load about the machine cycle as uniformly as possible, the timing of the arms is arranged to leave an equal or substantially equal interval between their operation, and then the positions of the various sections is selected to cause all of the sections to deliver their signatures between the carrier pins.

I claim as my invention:

1. In a signature gathering machine, a frame, an endless conveyor extending along the front side of the machine, a plurality of signature hoppers disposed along the back side of the machine, a plurality of signature gathering sections each including a group of gripper arms adapted to transfer signatures from their respective hoppers to said conveyor and then return to their respective hoppers to complete a swing cycle, a shaft having its group of arms keyed thereto for movement in unison to simultaneously deliver a group of signatures to said conveyor, an actuating arm keyed to said shaft, a crank, a connecting rod pivotally connected at its one end to said actuating arm and connected at its other end to said crank, the cranks of the several sections being provided on a common crank shaft and disposed at different angular positions about the axis of said shaft, the gripper arms of each section being out-of-phase with the arms of the adjacent sections to distribute the operating load about the swing cycle.

2. In a signature gathering machine, a conveyor having equidistantly spaced carrier pins mounted thereon, a plurality of signature gathering sections disposed in end-to-end relation along said conveyor and including a plurality of hoppers, each section having a plurality of

gripper arms spaced apart a distance equal to the spacing of said carrier pins and supported for swinging movement in unison to simultaneously deliver a group of signatures from their respective hoppers to said conveyor and then return to said hoppers to complete the swing cycle, and crank means to position the gripper arms of the several gathering sections in out-of-phase relationship at equally spaced positions throughout their swing cycle, said sections being arranged along said conveyor to cause the gripper arms of the respective sections to deliver their signatures between the carrier pins mounted on said conveyor.

3. In a signature gathering machine, a conveyor having equidistantly spaced carrier pins mounted thereon, a plurality of signature gathering sections disposed in end-to-end relation along said conveyor and including a plurality of hoppers, each section having a plurality of gripper arms spaced apart a distance equal to the spacing of said carrier pins and supported for swinging movement in unison to simultaneously deliver a group of signatures from their respective hoppers to said conveyor and then return to said hoppers to complete the swing cycle, a crankshaft extending along the several gathering sections, a plurality of cranks provided on said shaft, said cranks being circumferentially spaced about the axis of said shaft, the gripper arms of each section being out-of-phase with the gripper arms of the adjacent sections, and means connecting each crank to the gripper arms of its respective gathering section, said sections having their positions with respect to said conveyor predetermined to cause the gripper arms of the respective sections to deliver their signatures between the carrier pins mounted on said conveyor.

4. In a signature gathering machine, a frame, a conveyor extending along the front side of the machine having equidistantly spaced carrier pins mounted thereon, a plurality of signature hoppers disposed along the back of the machine, a plurality of gathering sections each including a group of gripper arms supported for swinging movement on said frame to transfer signatures from their respective hoppers to said conveyor and then return to said hoppers to complete the swing cycle, an actuating mechanism provided for each group of gripper arms, said actuating mechanisms being arranged to dispose each group of gripper arms out-of-phase with the arms of the adjacent sections throughout the swing cycle to provide a balanced machine, and a common drive means for said actuating mechanisms, the position of each group of gripper arms with respect to said conveyor being predetermined to cause the gripper arms of each group to deliver their signatures between the carrier pins mounted on said conveyor.

5. In a signature gathering machine, a frame, a conveyor extending along the front side of the machine having equidistantly spaced carrier pins mounted thereon, a plurality of signature hoppers disposed along the back of the machine, a plurality of gathering sections each including a group of gripper arms supported for swinging movement on said frame to transfer signatures from their individual hoppers to said conveyor and then return to said hoppers to complete the swing cycle, an actuating mechanism provided for each group of gripper arms, said actuating mechanism including cranks arranged to dispose the several groups of gripper arms at different

relative positions in out-of-phase relationship throughout the swing cycle to provide a balanced machine, said cranks being provided with a common drive means, and the position of each group of gripper arms with respect to said conveyor being predetermined to cause the gripper arms of each group to deliver their signatures between the carrier pins mounted on said conveyor.

6. In a signature gathering machine, a frame, 10 an endless conveyor extending along the front side of the machine having equidistantly spaced carrier pins mounted thereon, a plurality of signature hoppers disposed along the back side of the machine, a plurality of individual gathering sections each including a group of swinging arms to transfer signatures from their respective hoppers to said conveyor and then return to said hoppers to complete the swing cycle, a shaft having its group of arms keyed thereon for movement in unison to simultaneously deliver a group of signatures to said conveyor, an actuating arm keyed to said shaft, a crank, a connecting rod pivotally connected at its one end to said actuating arm and connected at its other end to said crank, the cranks of the several individual sections being disposed at different positions to dispose the several groups of gripper arms in out-of-phase relationship throughout the swing cycle, and a common drive means for said cranks, said groups of swinging arms having their positions with respect to said conveyor predetermined to cause the arms of the respective groups to deliver their signatures between the carrier pins mounted on said conveyor.

7. In a signature gathering machine, a movable conveyor to receive and support signatures for movement along the machine, a plurality of individual signature gathering sections arranged in end-to-end relation along one side of said conveyor, each section comprising a plurality of signature hoppers equally spaced along said conveyor and a plurality of gripper arms supported on a common axis for common pivotal movement to simultaneously engage and transfer signatures from their respective hoppers onto said conveyor and then return to their respective hoppers to complete a swing cycle, means to move the conveyor and signatures thereon a distance equal to the distance between centers of adjacent hoppers of each gathering section during each swing cycle of the gripper arms, a crankshaft extending along the several gathering sections and including a crank for each section and connecting rods connecting the cranks to their respective gripper arms, the cranks and gripper arms of the several gathering sections being arranged in different positions throughout the swing cycle in out-of-phase relationship to distribute the operating load about the swing cycle.

8. In a signature gathering machine, a movable conveyor to receive and support signatures for movement along the machine, a plurality of individual signature gathering sections arranged in end-to-end relation along one side of said conveyor, each section comprising a plurality of signature hoppers equally spaced along said conveyor and a plurality of gripper arms supported on a common axis for common pivotal movement to simultaneously engage and transfer signatures from their respective hoppers onto said conveyor and then return to their respective hoppers to complete a swing cycle, means to move the conveyor and signatures thereon a distance equal to the distance between centers of adjacent hoppers

of each gathering section during each swing cycle of the gripper arms, a crankshaft extending along the several gathering sections and including a crank for each section and connecting rods connecting the cranks to their respective gripper arms, the cranks and gripper arms of each section being out-of-phase with the cranks and gripper arms of the adjacent sections whereby the operating load is distributed about the swing cycle.

9. In a signature gathering machine, a movable conveyor to receive and support signatures for movement along the machine, a plurality of individual signature gathering sections arranged in end-to-end relation along one side of said conveyor, each section comprising a plurality of signature hoppers equally spaced along said conveyor and a plurality of gripper arms supported on a common axis for common pivotal movement to simultaneously engage and transfer signatures from their respective hoppers onto said conveyor and then return to their respective hoppers to complete a swing cycle, means to move the conveyor and signatures thereon a distance equal to the distance between centers of adjacent hoppers of each gathering section during each swing cycle of the gripper arms, a crankshaft extending along the several gathering sections and including a crank for each section and connecting rods connecting the cranks to their respective gripper arms, the cranks and gripper arms of the several sections being in out-of-phase relationship at substantially equally spaced positions through the swing cycle whereby the operating load is distributed about the swing cycle.

10. In a signature gathering machine, a movable conveyor to receive and support signatures for movement along the machine, a plurality of individual signature gathering sections arranged

in end-to-end relation along one side of said conveyor, each section comprising a plurality of signature hoppers equally spaced along said conveyor and a plurality of gripper arms supported on a common axis for common pivotal movement to simultaneously engage and transfer signatures from their respective hoppers onto said conveyor and then return to their respective hoppers to complete a swing cycle, means to move the conveyor and signatures thereon a distance equal to the distance between centers of adjacent hoppers of each gathering section during each swing cycle of the gripper arms, a crankshaft extending along the several gathering sections and including a crank for each section and connecting rods connecting the cranks to their respective gripper arms, the cranks and gripper arms of the several sections being in out-of-phase relationship at substantially equally spaced positions through the swing cycle whereby the operating load is distributed about the swing cycle, the distance between centers of the last hopper of one section and the first hopper of the adjacent section in the line of travel of the conveyor being equal to the distance the conveyor travels during movement of the gripper arm of said first hopper to one point in the swing cycle after the gripper arm of said last hopper is disposed at said one point.
